UNITED STATES PATENT OFFICE

2,513,082

INDUCTION STIRRER

Ludwig Dreyfus, Västerås, Sweden, assignor to
 Allmanna Svenska Elektriska Aktiebolaget,
 Västerås, Sweden, a corporation of Sweden

Application November 19, 1945, Serial No. 629,458
 In Sweden November 30, 1944

3 Claims. (Cl. 13—26)

1

It is known to provide metallurgical furnaces, especially electric arc furnaces, with a multi-phase electrical winding beneath the bottom of the furnace hearth, said winding being fed by low frequency alternating currents and serving to produce, by induction, a motion of the molten contents of the furnace around a horizontal axis. Such a winding has heretofore been arranged between the masonry of the furnace and the sheet metal shell serving to support and reinforce the said masonry, the said shell consisting of magnetic iron and serving as a return path or yoke for the magnetic flux penetrating the molten furnace contents. While such a construction is quite satisfactory in electromagnetic respect, it has been found to have the disadvantage, that if the masonry should be damaged in some way by heat or chemical action or otherwise, there is a risk of the winding being damaged by heat action.

It has now been found, that in using such low frequencies of the alternating current which are suitable for the stirring of the bath, and which in large furnaces should be about one cycle per second or less, and in manufacturing the shell supporting the furnace, or at least the bottom of said shell, of non-magnetic material having a high electric resistivity, for instance of non-magnetic sheet iron, it is possible to place the stirring winding outside, i. e. beneath, the supporting shell bottom and still to induce sufficiently strong eddy currents in the bath to obtain the desired stirring action, without inducing so strong currents in the shell as to cause a non-permissible heating thereof or an appreciable loss of power therein. Because of the non-magnetic nature of the shell it forms no return path for the flux from the windings and therefore does not divert this flux from the contents of the furnace. A metallurgical furnace, especially an electric arc furnace, provided with a stirring winding arranged in this manner, forms the object of the present invention. The stirring winding should preferably be arranged in slots in a separate shell of magnetic material, said shell being preferably laminated, although with considerably thicker sheet iron than in usual laminations, for instance with a thickness of about 1 centimeter or more.

A form of the invention is illustrated in the accompanying drawing in a plan view with the furnace body removed in Fig. 1 and in a side view with part of the furnace body in section in Fig. 2.

1 represents the masonry of the furnace body and 2 a shell serving to reinforce the said masonry at its periphery. The said shell has, at the bottom, a continuation 9 of non-magnetic sheet iron, with which it may be connected by a welded joint 10. Beneath the bottom shell 9, there is placed a laminated shell of magnetic iron 3 with slots open upwards and containing

2

a two-phase winding, which consists of a central coil 4 fed by current of one phase and two lateral coils 5 fed by current of another phase, preferably with a phase difference of 90°.

Some of the plates forming the laminated shell may have a larger height (at 6) than is required for magnetic reasons, in order to constitute a mechanically rigid construction. The same plates or other strengthening structures may be directly secured to the shell 2 at one end at 7 and connected thereto by links 8 at the other end, in order to permit a mutually different heat expansion.

I claim as my invention:

1. In a metallurgical furnace, a masonry hearth adapted to hold a liquid charge, a multi-phase winding mounted below said hearth, means for feeding said winding by a multiphase current having a frequency of the order of one cycle per second at most, and a continuous protective sheet metal shell of non-magnetic metal of high electric resistivity between said winding and said hearth, said shell reinforcing said hearth and protecting said winding against heat damage resulting from damage to said hearth.
2. In a furnace as claimed in claim 1, a shell of magnetic material below said first shell having thick laminations and provided with slots therein, said windings being mounted in said slots.
3. In a furnace as claimed in claim 2, expansion joints connecting said shells.

LUDWIG DREYFUS.
